UNITED STATES PATENT OFFICE

GALE L. FERGUSON, OF CLEVELAND, OHIO, ASSIGNOR, BY MESNE ASSIGNMENTS, TO
AUTO PRIME PUMP COMPANY, OF CLEVELAND, OHIO, A CORPORATION OF OHIO

PUMPING APPARATUS

Application filed December 12, 1927. Serial No. 239,367.

The present invention relates, as indicated, to a pumping apparatus, and more particularly to an improved automatically primed centrifugal or peripheral speed pump, and the primary object of the invention is to provide in combination with a pump of the type indicated apparatus through the agency of which water or other liquid may be satisfactorily lifted from a level substantially 5 below the level of the pump. To the accomplishment of the foregoing and related ends, said invention, then, consists of the means hereinafter fully described and particularly pointed out in the claims.

15 The annexed drawing and the following description set forth in detail certain mechanism embodying the invention, such disclosed means constituting, however, but one of various mechanical forms in which the 20 principle of the invention may be used.

In said annexed drawings:

Fig. 1 is an elevation partly in section of the pump casing and a section of priming chamber, showing the cover plate of such casing removed; Fig. 2 is a section of the pump taken substantially on the line 2—2 of Fig. 1; and Fig. 3 is a perspective view of the cover plate.

Referring more particularly to the figures, 30 the reference numeral 1 indicates a priming chamber connected through a check valve 2 with a suitable source of liquid supply, and having an outlet connection 3 adjacent its bottom. A pump casing 4 provides an impeller chamber 5 adapted to receive a pair of mating rings 6 and 7 and provided on their abutting faces with annular grooves co-operating to form a pump channel 8. Within the chamber 5 there is mounted an impeller 9 carried by shaft 10 extending outwardly of the casing, and said impeller 9 extends into the pump channel 8.

The casing 4 is provided adjacent its bottom with an inlet connection 11 and at its 45 top with an outlet connection 12 communicating with the impeller chamber 5 through a curved conduit 14 formed in the casing.

The side of the casing opposite that through which the shaft 10 extends is open, 50 and is adapted to be closed by a cover plate

15 provided with a curved conduit 16 in its upper end communicating as at 17 with the impeller chamber 5 and as at 18 with the bore 19 of the outlet connection 12. Thus it will be seen that the outlet connection 12 55 communicates with the impeller chamber 5 through the two passages 14 and 16.

A pipe 20 connects the outlet connection 3 of the priming chamber 1 with the inlet connection 11 of the pump casing 4. The 60 pump channel 8 is provided with a branched inlet port 21 communicating with the passage 22 in the inlet connection 11 of the casing on opposite sides of the impeller 9. Said pump channel 8 is further provided with 65 an inwardly opening branched outlet port 21' communicating on opposite sides of the impeller 9 with the impeller chamber 5. It will be noted that a slight clearance is provided between the pump rings 6 and 7 and 70 the respective sides of the impeller 9.

When the pumping apparatus is first installed, the priming chamber 1 is filled by any desired means, and it will be obvious that the pump channel 8 and the impeller 75 chamber 5 will be filled to a corresponding level because of the connection 20 and the clearances 23 and 24. If, now, the impeller 9 is rapidly rotated in the direction of the arrow shown in Fig. 1, liquid will be drawn 80 from the priming chamber in through inlet port 21 and will be ejected through the outlet port 21' of the pump channel 8. Simultaneously, the liquid in the impeller chamber 5 will be given a swirling motion and will 85 assume an annular shape, constantly attempting to enter the pump channel through the clearances 23 and 24, and at the same time finding egress through the passages 14 and 16 to the outlet connection 12 and the line 90 connected therewith. As the level of the liquid in the priming chamber 1 falls, due to exhaustion by the pump, the pressure in the upper portion of said chamber will be lowered, and a corresponding lowering of the 95 pressure in the supply line will cause the liquid from the source of supply to rise in said supply line. Eventually, if the liquid source is sufficiently below the level of the pump, the liquid level in the priming cham-

ber 1 will be drawn below the top of the outlet connection 3, and air will be drawn into the pump channel 8 in small amounts. The air bubbles thus drawn into the channel 8 will be forced out through the outlet port 21' into the impeller chamber 5, and will rise through the liquid in said impeller chamber and any liquid which may stand in the passages 14, 16 and 19 and will flow into the service line. As soon as air begins to be drawn into the pump, the pressure in the delivery line from the pump will fall, and liquid will cease to be delivered and will stand at some equilibrium level probably in the outlet connection 12, but possibly in the impeller chamber 5.

As will be readily understood, however, the swirling of the liquid in the chamber 5 will cause such liquid to retain its annular shape and to continue to prime the pump through the clearances 23 and 24. Thus the pump will act, for as long as may be necessary, as an air pump exhausting air from the priming chamber 1 and from the supply line connected thereto through the valve 2. Eventually, the pressure in the priming chamber 1 and its supply line will be sufficiently lowered to cause the liquid from the source to rise in said supply line sufficiently to enter the priming chamber 1 and to fill said chamber, thus preventing the entrance of more air into the pump. Once the outlet connection 3 is sealed by the liquid, air ceases to be drawn in the pump channel 8, and the impeller chamber 5 is filled with liquid, after which the desired delivery of liquid through the outlet connection 12 begins.

It is to be understood that the above described cycle takes place only upon the original installation of the pump, or when, from some untoward accident the valve 2 has leaked to allow the liquid level in the supply pipe to fall. Ordinarily, the priming chamber 1 will stand full of liquid as will the supply pipe, and as soon as the pump is started, liquid drawn from the priming chamber 1 will be immediately replaced by liquid entering said chamber through the supply pipe and valve 2.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a pump, a casing providing a chamber and an inlet and outlet communicating therewith, and means forming a pump channel within said chamber, said pump channel being provided with an inlet port registering with said casing inlet and said pump channel being further provided with an outlet port opening into the interior of said chamber.

2. In a pump, a casing, providing a chamber, and an inlet and outlet communicating therewith, a pair of annular rings within said chamber and forming a pump channel, an impeller extending into said channel, said channel being formed with an inlet port registering with said casing inlet, and with an outlet port opening into said chamber.

3. In a pump, a casing providing a chamber having an inlet adjacent its bottom and an outlet at its top, a pair of annular pump rings within said casing cooperating to form a pump channel, an impeller extending into said channel, said channel being provided with an external inlet port registering with said casing inlet, and with an internal outlet port opening into said chamber.

4. In a pump, a casing providing a chamber having an inlet adjacent its bottom and a branched outlet at its top, a pair of annular pump rings within said casing cooperating to form a pump channel, an impeller extending into said channel, said channel being provided with an outwardly directed branched inlet port registering with said casing inlet, and with an inwardly directed branched outlet port opening into said chamber.

5. Pumping apparatus comprising the combination with a priming chamber having an outlet adjacent its bottom, of a casing providing an impeller chamber having an inlet adjacent its bottom and an outlet at its top, means connecting said priming chamber outlet with said impeller chamber inlet, a pair of annular pump rings in said impeller chamber cooperating to form a pump channel, said channel being provided with an outwardly directed inlet port registering with said casing inlet and an inwardly directed outlet port opening into said chamber, an impeller in said impeller chamber extending into said pump channel and adapted, when rotated, to cause flow of fluid through said pump channel from said inlet through said outlet port, and means to rotate said impeller.

Signed by me this 8th day of December, 1927.

GALE L. FERGUSON.
